VALVE SPRING COMPRESSOR AND LIFTER

Filed Aug. 8, 1928

FIG. 2.

FIG. 4

FREDERICK F. FOREMAN, Inventor

By *Samuel H. Davis,*

Attorney

UNITED STATES PATENT OFFICE

FREDERICK F. FOREMAN, OF LANSING, MICHIGAN, ASSIGNOR OF ONE-HALF TO
PATRICK H. FAHEY, OF HUBBARDSTON, MICHIGAN

VALVE-SPRING COMPRESSOR AND LIFTER

Application filed August 8, 1928. Serial No. 298,349.

This invention relates to valve spring compressors and lifters, and belongs to that class of appliances designed and used for seizing and compressing a spring located in the valve mechanism or like situation, in order that the spring may be readily removed and reseated by the expenditure of a minimum of time and effort.

The object of this invention is the production of a device of the type stated having parts of special construction and arrangement, whereby it is believed a particularly strong and effective tool for the purpose is made, the manufacture of this invention being unusually easy and cheap especially in quantities.

This invention consists essentially of a pair of jaws movable parallel one with the other, and operated by a reciprocating rod in the body of the invention, moved powerfully back and forth by means of a revoluble spirally grooved disk or member carried by the body and engaging a suitable projection or projections carried by the rod.

In the accompanying drawings setting forth the construction and disposition of the various parts of this invention,

Fig. 1 represents a side view of all parts assembled.

Fig. 2 is a top view of all the parts partly in section.

Fig. 3 is a view of the spiral and revoluble member alone, illustrating the grooves in the said member.

Fig. 4 is a view of a portion of the body part of this invention in section, showing the reciprocative operating rod therein, and the projection or projections carried by the rod to engage the groove of the spiral member.

In Figs. 3 and 4 the scale of drawing has been slightly increased.

Throughout the description and drawings the same number is used to refer to the same part.

Considering the drawings, the handle 1 has at the end a removable screw plug 2 closing the end of a tubular shank or body 3 of the invention. The outer portion 4 of the body may be slightly reduced in diameter,

or rounded and terminated by an expanding head 5.

A longitudinally sliding rod 6 occupies the body 3 movably, and it is to admit oil to the sliding rod and the tubular body and to close the end of the body that the screw plug 2 is introduced. The rod 6 is made with one or more projections 7, which are arranged to engage and act with the groove 8 of a spiral disk or member 9. The member 9 is revoluble by means of finger pieces 10 on a pintle 11.

The outer end of the sliding rod 6 is threaded and marked 12 in Fig. 1, and it is provided with an adjustable cross-head 13 equipped with projecting pins 14 and 15 at the ends. The pins engage and travel slots 16 and 17 extending lengthwise in links 18 and 19. Those links have a common pivotal junction 20 with the head 5 of the body 4, and they are attached pivotally at their outer extremities by the pivot screws 21 and 22 to the parallel jaw bars 23 and 24, best shown in Fig. 1. The parallel jaw bars are usually constructed with angularly disposed end pieces of forked formation marked 25 and 26. Either or both of the end pieces 25 and 26 may be adjustable and they are intended to engage a spring 27 of a valve to remove or to reseat the spring, or for other like purposes. At their other or right hand ends as set forth in Fig. 1 the jaw bars 23 and 24 have pivotal links 28 and 29 connected at a common pivotal point with the body or shank 3.

In the operation of this invention, if it is to be used on a longer spring than the distance between the jaws will normally accommodate, the adjustable forked end 25 may catch the spring 27 at any coil. Then, if the revoluble spiral member 9 be suitably turned the rod 6 will be reciprocated to the left hand, and a very powerful effect exerted upon the links 21 and 22 by the cross-head pins 14 and 15. The result is that the jaw bars 23 and 24 move towards each other and the forks or ends 25 and 26 compress the spring enabling the whole to be moved carrying the spring. Contrary movement reseats the spring and permits its expansion into its former location.

Having now described this invention, and explained the mode of its operation, I claim:—

1. In a valve compressor and lifter, the combination with a body portion, of a rod arranged to be reciprocated longitudinally in the body, clamping jaws carried by the said body, means for supporting the jaws upon the body whereby the jaws are movable parallel with each other and towards and from each other, devices carried by the rod and acting upon the said supporting means to move the jaws, and means for actuating the rod comprising a spirally grooved member transversely and rotatively carried by the body, means formed upon the said member for rotating the same by hand, and a tooth borne by the rod in engagement with the said spiral.
2. In a valve compressor and lifter, the combination with a body portion, of a rod arranged to be reciprocated longitudinally in the body, clamping jaws carried by the said body, means for supporting the jaws comprising pairs of parallel links pivotally attached to the said body and to the jaws, devices carried by the rod and acting upon the said links to move the jaws, and means for actuating the rod comprising a grooved member rotatively carried by the said body and provided with finger pieces whereby the member may be rotated, and a projection borne by the rod and arranged in engagement with the groove of the said member.
3. In a valve compressor and lifter, the combination with a body portion, of a rod arranged to be reciprocated longitudinally in the body, clamping jaws carried by the said body, means for supporting the jaws comprising pairs of parallel links pivotally attached to the body and to the jaws, the links of the pair of links located towards the outer ends of the jaws having lengthwise slots, and pins carried by the said rod and acting upon the said slots in the links to move the jaws, and means for actuating the rod comprising a spirally grooved member rotatively carried by the said body portion and a projection carried by the rod and arranged to engage the groove of the spiral.

In testimony whereof I affix my signature,
FREDERICK F. FOREMAN.
